Attest,

UNITED STATES PATENT OFFICE.

NIRAM AUSTIN CROMWELL, OF CHICAGO, ILLINOIS.

DESIGN FOR A CARBURETER.

48,855.

Specification for Design.

Patented Apr. 11, 1916.

Application filed August 28, 1915. Serial No. 47,872. Term of patent 14 years.

To all whom it may concern:

Be it known that I, NIRAM AUSTIN CROMWELL, a citizen of the United States, residing at Chicago, in the county of Cook and State of Illinois, have invented a new, original, and ornamental Design for a Carbureter, of which the following is a specification, reference being had to the accompanying drawing, forming a part thereof.

Figure 1 is a top plan of a carbureter showing my new design. Fig. 2 is a side elevation. Fig. 3 is an end elevation.

I claim—

The ornamental design for a carbureter as shown.

In witness whereof, I hereunto subscribe my name to this specification.

NIRAM AUSTIN CROMWELL.
